PHILO B. TINGLEY, OF NEW YORK, N. Y.

RE-ALINING MECHANISM FOR WRITING-MACHINES.

1,312,063.

Specification of Letters Patent.

Patented Aug. 5, 1919.

Application filed December 28, 1918. Serial No. 268,596.

To all whom it may concern:

Be it known that I, PHILO B. TINGLEY, a citizen of the United States, residing at 234 West 104th street, New York, county of New York, State of New York, have invented an Improvement in Re-Alining Mechanism for Writing-Machines, of which the following is a specification.

This invention has for its object to provide novel mechanism that may either be built into new machines or applied as an attachment to machines already in use, and that will enable the operator to detach the platen from the ratchet, leaving the ratchet locked and the platen free to be turned forward or backward, thus enabling him to turn the platen so as to bring any particular line on the paper exactly on the writing line of the machine (as in the case of forms ruled to harmonize with the ratchet) without shifting the paper relatively to the platen, and then locking the ratchet to the platen, which now holds the paper accurately in position to receive the writing.

My novel mechanism may be used either in connection with the regular spacing mechanism, or in connection with variable spacing mechanism, as, for example, the spacing mechanism of my Patent No. 1,118,074, dated November 24th, 1914.

In the accompanying drawing forming a part of this specification I have illustrated the use of my novel realining mechanism in connection with the ordinary spacing mechanism of a writing machine.

Figure 1 is a plan view of so much of a writing machine as is necessary to illustrate the application thereto of my novel realining mechanism;

Fig. 2 an end elevation corresponding therewith, the hand wheel being removed and the shaft in section on the line 2—2 in Fig. 1;

Fig. 3 a view on an enlarged scale, partly in elevation and partly in section on the line 3—3 in Fig. 2, looking in the direction of the arrows;

Fig. 4 a section on the line 4—4 in Fig. 3, looking in the direction of the arrows, and

Fig. 5 is a section on the line 5—5 in Fig. 1, looking in the direction of the arrows.

10 denotes the carriage which may be of any ordinary or preferred construction, 11 the shaft, 12 the platen which is rigidly se-

cured to the shaft, 13 the spacing ratchet, 14 the hand wheel, 15 the spacing pawl and 16 the stop pawl both of which operate in the usual manner.

The present invention requires that the shaft, carrying the platen, be rotatable independently of the ratchet, that the ratchet, which may be a special ratchet or the regular spacing ratchet as shown in the drawing, be secured to the shaft by a clutch, and that the hand wheel be longitudinally movable to operate the clutch. In the present instance I have shown the hand wheel as carried by an auxiliary shaft lying in alignment with the platen shaft. The use of an auxiliary shaft, however, is immaterial so far as the principle of the invention is concerned. In applying the invention to new machines the platen shaft may be extended sufficiently to provide for my novel realining mechanism, or in applying the realining mechanism to an old machine a longer platen shaft may be substituted to provide for the realining mechanism. In the drawing, however, I have illustrated a form of the invention using an auxiliary shaft which avoids changing the platen shaft.

20 denotes a shouldered hub which is secured to the shaft by means of a clamp, 85 which in turn is secured to the hub by a screw 34, and comprises arms 33 which inclose the shaft and are clamped about it by a screw 35, the ratchet lying loosely between the clamp and the shoulder on the hub. 90

The body of the clutch is made in a single piece and comprises an attaching lug 17 by means of which the clutch as a whole is rigidly secured to the ratchet, as by a rivet 18, and jaws 19 which inclose the hub. The 95 hand wheel is provided with a hub 21 and an offset flange 22, and is adapted to slide on an auxiliary shaft 23 which is angular, or flattened on one or more sides, in order to hold the hand wheel against rotation independently of said shaft while permitting it to slide freely thereon. The inner end of the auxiliary shaft is threaded, as at 24, and is turned into a threaded hole in the hub, the platen shaft lying in an unthreaded hole 100 in the other end of the hub. The enlarged head of a screw 36 engaging the outer end of the auxiliary shaft retains the hand wheel thereon. The clutch jaws are provided near their free ends with holes, transverse to the shaft, which receive bushings 25, provided respectively with right and left internal

threads which are engaged by a right and left center screw 26. This center screw is provided, between the jaws, with an angular block 27 on which the clutch lever 28 is mounted. The clutch lever is provided with branches 29 adapted to bear on opposite sides of the flange on the hand wheel. The free ends of the jaws are enlarged to provide ample support for the bushings and are provided with slots 30, see Fig. 3 in connection with Fig. 4, so as to provide spring clamps for the bushings, which are secured by means of screws 31 which pass freely through the outer arms of the clamps, indicated specifically by 32, and engage the other arms which are integral portions of the clutch jaws.

The operation is as follows: As shown in Fig. 3 the hand wheel is moved outward to its extreme position and the clamp has been operated to lock the ratchet to the shaft. The parts remain in this position under the ordinary conditions of use. Suppose now that it is required to detach the platen from the ratchet, as in positioning a ruled form in the machine, the operator moves the hand wheel inward which causes flange 22 to actuate the clutch lever and impart a reverse rotary movement to the center shaft. The effect is, through the engagement of this screw with the right and left threaded bushings, to separate the jaws slightly and thereby release their grip on the hub which, as already explained, is locked to the shaft by means of clamping arms 33 and screws 34 and 35. This leaves the ratchet disconnected from the platen but locked against rotation by the pawl, in the present instance the stop pawl. The platen may now be rotated freely by means of the hand wheel which enables the operator to place the paper wherever it may be required without any shifting of the paper relatively to the platen. If the use of the realining mechanism has been to position a sheet of paper or a form, the hand wheel is moved outward again to lock the ratchet to the shaft as soon as the paper or form is in place. This movement through the action of flange 22, the jaw lever, and the center screw is to cause the jaws to grip the hub and thus lock the ratchet and platen together. The operation of the machine will then proceed as usual, the spacing being performed by the engagement of the spacing pawl with the ratchet. If the clutch does not grip tightly enough it may be readily adjusted by loosening one of the screws 31, turning the bushing slightly and then locking it again. The thread of the bushing may thus be either advanced or retarded, as may be required, to make the grip greater or less, or, should it be desirable to give the center screw reverse action, such action may be obtained by interchanging the bushings. Pushing the hand wheel inward would then

cause the jaws to grip the hub instead of to release it.

When the realining mechanism is used with variable spacing mechanism, the ratchet does not perform the function of a spacing ratchet, the spacing operation being performed by the variable spacing mechanism and the ratchet being normally loose on the shaft, whereas when serving as a spacing ratchet it must be fixed to the shaft. In using the realining mechanism in connection with variable spacing mechanism, the ratchet is held stationary by the stop pawl. The notch engaged by the stop pawl corresponds with the line that was being written at the time the ratchet was locked. The paper may then be turned freely by means of the hand wheel. After making the correction the platen is returned to the writing line, that is the platen is turned until the pawl is in engagement with the same notch it engaged at the time the ratchet was locked to the platen. In other words the paper is returned with perfect accuracy to the writing line of the machine. The ratchet is now disconnected from the platen and remains stationary until its services are called for again. Without the aid of the ratchet the operator would have to realine the work entirely by sight, which is both difficult and tiresome, whereas with the aid of the ratchet he only has to be sure that he stops at the right notch, which the merest glance will show.

Having thus described my invention, I claim:

1. Mechanism of the character described comprising a hub, a clamp rigidly secured to the hub and adapted to grip a shaft, a ratchet rotatably mounted on the hub, a clutch secured to the ratchet and having jaws inclosing the hub, means for causing the jaws to grip and release the hub, and a pawl for locking the ratchet against rotation when released.

2. Mechanism of the character described comprising a hub adapted for attachment to a shaft, a ratchet rotatably mounted on the hub, a clutch rigidly secured to the ratchet and having jaws inclosing the hub, a right and left threaded screw engaging the jaws, means for oscillating the screw, whereby the jaws are caused to grip and release the hub, and means for locking the ratchet against rotation when released.

3. Mechanism of the character described comprising a hub adapted for attachment to a shaft, a ratchet rotatably mounted on the hub, a clutch rigidly secured to the ratchet and having jaws inclosing the hub, right and left threaded bushings in the jaws, a right and left threaded screw engaging the bushings, means for oscillating the screw, and means for locking the ratchet against rotation when released from the hub.

4. Mechanism of the character described comprising a hub adapted for attachment to a shaft, a ratchet rotatably mounted on the hub, a clutch rigidly secured to the ratchet and having jaws inclosing the hub, a right and left threaded screw, a lever secured to the screw centrally and having branches, a longitudinally movable hand wheel having a flange engaged by the lever branches where-
5 by the clutch is operated, and means for locking the ratchet against rotation when released.
5. In combination a platen shaft, a hub carried thereby, a ratchet rotatably mounted on the hub, a clutch secured to the ratchet and having jaws inclosing the hub, a right and left threaded screw by which the clutch jaws are operated, a lever secured to said screw, an auxiliary shaft secured to the hub in alinement with the platen shaft, a hand wheel longitudinally movable on the auxiliary shaft and fixed against independent rotation, whereby the clutch lever is operated, and means for locking the ratchet against rotation when released from the hub.

6. In combination a platen shaft, a hub carried thereby, a ratchet rotatably mounted on the hub, a clutch carried by the ratchet and having jaws inclosing the hub, a right and left threaded screw by which the jaws are operated, and means for locking the ratchet against rotation when released from the hub.
30
7. In combination a platen shaft, a hub carried thereby, a ratchet rotatably mounted on the hub, a clutch carried by the ratchet and having jaws inclosing the hub, a right and left threaded screw by which the jaws
- are operated, a branched lever secured to the screw, an auxiliary shaft secured to the hub in alinement with the platen shaft, a hand wheel longitudinally movable on the auxiliary shaft and fixed against independent rotation, a flange upon the hand wheel which is engaged by the branches of the lever, and means for locking the ratchet against rotation when released from the hub.
40
- 45
8. In combination a platen shaft, a hub carried thereby, a ratchet mounted to oscillate on the hub, a clutch carried by the ratchet and adapted to engage the hub, an auxiliary shaft secured to the hub in alinement with the platen shaft, a hand wheel longitudinally movable on the auxiliary shaft and fixed against independent rotation, operating connections between the hand wheel and the clutch, and means for locking the ratchet against rotation when released from the hub.
50
- 55
9. In combination a platen shaft, a hub carried thereby, a ratchet mounted to oscillate on the hub, a clutch carried by the ratchet and adapted to engage the hub, a right and left threaded screw by which the clutch is operated, a branched lever secured to said screw, an auxiliary shaft secured to the hub in alinement with the platen shaft, a hand wheel longitudinally movable on the auxiliary shaft and fixed against independent rotation, said hand wheel being pro-
